UNITED STATES PATENT OFFICE

2,541,588

AIR INJECTION SMOKE-CONSUMING
STRUCTURE FOR FURNACES

Leighton P. Kerruish, Steelville, Mo.

Application July 15, 1947, Serial No. 760,975

2 Claims. (Cl. 110—73)

1

This invention relates to improvements in smoke consumers for use in connection with boilers or furnaces.

A principal object of the invention is to provide a simply constructed and efficient device of this character, which is designed to commingle the products of combustion with fresh heated air, whereby all the smoke is consumed before being discharged through the smoke flue.

A preferred embodiment of the invention is illustrated in the accompanying drawings, but it is understood that modifications may be made therein without departing from the spirit of the invention as hereinafter claimed.

Figure 1 represents a longitudinal vertical section through a heating system equipped with the new and improved smoke consumer.

Figure 2 is a plan view of the structure of Figure 1.

Figure 3 is a vertical section through a nozzle for discharging fresh heated air into the combustion chamber to commingle with the products of combustion.

With particular reference to the drawings, a heating system is illustrated as comprising a floor 1, a pair of spaced longitudinal side walls 2 and 3 positioned on the floor 1, and a fire box 4 positioned longitudinally of and between the side walls 2 and 3. A vertically disposed bridge wall 20 for deflecting the heat upwardly against the boiler 22 is positioned transversely of and between the side walls 2 and 3 adjacent the fire box 4. Arranged in parallel spaced relation with respect to the bridge wall 20 between the side walls 2 and 3 is a vertically disposed baffle wall 14, the latter wall 14 forming with the bridge wall 20 and the adjacent portions of the side walls 2 and 3 a combustion chamber 10. A second vertically disposed baffle wall 15 is arranged in parallel spaced relation with respect to the baffle wall 14 between the side walls 2 and 3 and forms with the wall 14 and the adjacent portions of the side walls 2 and 3 a second combustion chamber 11. The baffle walls 14 and 15 are each provided with openings, the openings being in the form of arches to permit gas flow therethrough. The wall 14 has three such arches 18, Figure 2, spaced from each other, and the wall 15 has three such arches 19 spaced from each other, each of the arches 18 and 19 extending down to the floor 1. A vertically disposed outside wall 21 is arranged in parallel spaced relation with respect to the baffle wall 15 between the side walls 2 and 3 and forms with the wall 15 and the adjacent portions of the side walls 2 and 3 a flue chamber 12. Po-

sitioned between the side walls 2 and 3 intermediate the wall 15 and the wall 21 is a supporting column 23 for the boiler 22. The combustion chambers 10 and 11 also lead upwardly to the boiler. The products of combustion are intended to pass around the column 23 to a stack that leads to the outside atmosphere.

Incoming air is conducted through a pipe 25 to an electric fan blower 26 that is actuated by a motor 27. From the blower 26, the air passes into two horizontal branches 28 and 29, the branch 28 extending laterally of the combustion chamber 10 in the bottom of the bridge wall 20. Similarly, the branch 29 is positioned at the bottom of the baffle wall 14, and is somewhat lower in position than the branch 28 with respect to the chamber 10. Each of the branches 28 and 29 is provided with a series of nozzles 30, one type of which is shown in Figure 3 of the drawings. It will be observed that each nozzle 30 is directed diagonally toward the upper portion of the opposite wall of its respective combustion chamber.

In the operation of the device, the incoming air is forced through the branches 28 and 29 and through the nozzles 30, so that the ejected air has an upward circular motion, due to the convection currents of the heated products of combustion and due to the reflection from the roof of the combustion chambers. Consequently, the incoming air is thoroughly commingled with the products of combustion. As a result, a substantial proportion of the soot that passes over the bridge wall 20 is mixed with air in the first combustion chamber 10, and a substantial proportion of the remaining soot is caught in the second combustion chamber 11. As a result, very little, if any, soot or other solid matter is left by the time the products of combustion enter the flue chamber to go up the stack.

The positioning of the second branch 29 below the first branch 28 is to permit more thorough agitation of the incoming air with the products of combustion.

The efficiency of the system is increased by pre-heating the air passing through the branches 28 and 29, and this is effected by conducting a portion 31 of the inlet pipe 25 into the space 12 before the air goes to the blower 26.

If desired, a blow-off pipe 32 is mounted in the column 23 to blow sediment out of the boiler.

I claim:

1. In a heating system including a floor, spaced longitudinal side walls positioned on said floor, a firebox positioned longitudinally of and between said side walls, a vertically disposed bridge wall

positioned transversely of and between said side walls adjacent said firebox, a vertically disposed baffle wall arranged in parallel spaced relation with respect to said bridge wall and forming with the latter wall and the adjacent portions of said side walls a combustion chamber, a second vertically disposed baffle wall arranged in parallel spaced relation with respect to said first-named baffle wall and forming with the latter wall and the adjacent portions of said side walls a second combustion chamber, a vertically disposed outside wall arranged in parallel spaced relation with respect to said second-named baffle wall and forming with the latter wall and the adjacent portions of said side walls a flue chamber, there being openings extending through each of said first and second-named baffle walls, the openings in said first and second-named baffle walls being spaced from each other and each extending down to said floor, an inlet pipe, means for supplying air to said inlet pipe, a first branch pipe positioned in parallel relation with respect to the face of said bridge wall adjacent said first-named baffle wall and supported in said bridge wall and having one end connected to said inlet pipe, a second branch pipe positioned in parallel relation with respect to the face of said first-named baffle wall adjacent said second-named baffle wall and supported in said first-named baffle wall and having one end connected to said inlet pipe, and a plurality of upwardly directed nozzles arranged in spaced relation along each of said branch pipes for discharging the air from said pipes.

2. In a heating system including a floor, spaced longitudinal side walls positioned on said floor, a firebox positioned longitudinally of and between said side walls, a vertically disposed bridge wall positioned transversely of and between said side walls adjacent said firebox, a vertically disposed baffle wall arranged in parallel spaced relation with respect to said bridge wall and forming with the latter wall and the adjacent portions of said side walls a combustion chamber, a second vertical-

ly disposed baffle wall arranged in parallel spaced relation with respect to said first-named baffle wall and forming with the latter wall and the adjacent portions of said side walls a second combustion chamber, a vertically disposed outside wall arranged in parallel spaced relation with respect to said second-named baffle wall and forming with the latter wall and the adjacent portions of said side walls a flue chamber, there being openings extending through each of said first and second-named baffle walls, the openings in said first and second-named baffle walls being spaced from each other and each extending down to said floor, an inlet pipe, means for supplying air to said inlet pipe, a first branch pipe positioned in parallel relation with respect to the face of said bridge wall adjacent said first-named baffle wall and supported in said bridge wall and having one end connected to said inlet pipe, a second branch pipe positioned in parallel relation with respect to the face of said first-named baffle wall adjacent said second-named baffle wall and supported in said first-named baffle wall and having one end connected to said inlet pipe, and a plurality of upwardly directed nozzles arranged in spaced relation along each of said branch pipes for discharging the air from said pipes, said second-named branch pipe being disposed at a lower level than that of said first-named branch pipe.

LEIGHTON P. KERRUISH.
